SWITCH

John H. Benya, Lakewood, Ohio

Application June 26, 1933, Serial No. 677,607

8 Claims. (Cl. 200—81)

This invention relates to a switch particularly adapted for use in display devices of the type in which a succession of letters or other displays are caused to appear upon an electric sign. The present application is in part a continuation of my co-pending application Serial No. 497,426, Display device, filed November 22, 1930, to which reference is made for a general arrangement of mechanism in connection with which the switch which forms the subject matter of the present application is adapted to be used.

As in my earlier application, the switch contemplates the use of a body of mercury for making contacts and contemplates the employment of a difference in air pressure to actuate the switch.

To the accomplishment of the foregoing and related ends, said invention, then, consists of the means hereinafter fully described and particularly pointed out in the claims.

20 The annexed drawing and the following description set forth in detail certain mechanism embodying the invention, such disclosed means constituting, however, but one of various mechanical forms in which the principle of the invention may be used.

In the accompanying drawing Fig. 1 is a view partly in vertical section and partly in elevation of a preferred form of my improved switch; Fig. 2 is a horizontal section on the line 2—2 Fig. 1; Fig. 3 is a view corresponding to Fig. 2 but showing a modified form; Fig. 4 is a vertical central section through a further modification; and Fig. 5 is a horizontal section on the line 5—5 Fig. 4.

35 A detailed setting suitable for the various switches is shown in Fig. 1 of my application Serial No. 497,426. Fig. 1 of the present application illustrates a portion of the actuating apparatus which is shown more completely in Fig. 1 of my application Serial No. 497,426. This apparatus comprises a wall 11 defining a pressure chamber 15. Across the bottom 16 of the chamber a tape 17 perforated as at 18 and held down to the bottom board by cross bars 19 is movable. This is substantially a somewhat enlarged detail from Fig. 1 of Serial No. 497,426.

45 Any one of the illustrative forms of switch herein shown may be substituted for the J-shaped switches 14 of Serial No. 497,426. The circuit to an individual lamp is shown for each switch, the source of power being indicated by the reference character 12, as in Serial No. 497,426, while the lamp which the switch controls is indicated by the letter L, it being understood that the lamp L will ordinarily be one of a large number in a display, all taking power from the same source.

Referring now to the particular switch shown in Figs. 1 and 2, a tube 21 preferably of insulating material depends from the bottom board 16 and is open at the top through the board. This tube has side openings 22 some distance up from the bottom to permit the escape of air. Conductors 23 and 24 are led into the bottom and side of the tube, respectively, the contact of the conductor 24 being spaced some distance below the openings 22. A float 25 of any suitable material, for example 35 wood, hard rubber, phenolic condensation product, or the like, somewhat shorter than the tube and of somewhat less diameter, stands upright in the tube, floating on a small pool of mercury 26 in the bottom. The depth of the mercury is less than the distance from the bottom of the tube up to the contact 24.

In operation, when the movement of the tape 17 brings a perforation 18 into registry with the top of the tube, the air pressure is thus admitted 75 above the float 25 whereby a current of air strikes the top of the float and pushes the float down, thus sinking its lower end to some extent in the pool of the mercury 26 and raising the edges of the pool to make contact with the contact point 80 24, thus closing the circuit and lighting the lamp L. As the tape 17 moves on it again covers the top of the tube 21, but the air pressure thus held in the tube escapes through the clearance space 26' between the float and the tube and reaches 85 the atmosphere through the openings 22. Thus the pressure relieves itself and the float 25 rises, permitting the mercury to fall, breaking the circuit and extinguishing the light L.

The form illustrated in Fig. 3 is constructed 90 similarly to that of Fig. 1. Here the tube is designated as 31. The float 25 is the same as shown in Fig. 1 and clears the sides of the tube. The tube is vented as at 32, corresponding to the vents 22. An offset enlargement 31A at the bottom of the tube, defined on one side by a wall 31B, separates the mercury into two pools 36 and 36', mutually insulated by the wall 31B. A conductor 33 leads into the principal pool 36 and another conductor 34 leads into the side pool 36'. The wall 31B is slightly higher than the depth of the pool 36. When an air current is admitted to the top of the tube 31, it strikes the float 25, which sinks sufficiently to raise the mercury 36 to overflow the wall 31B, thus establishing electrical contact between the two pools of mercury and lighting the lamp L.

In Fig. 4 the tube 41 and its float 45 are square in cross section to prevent turning of the float. The float fits loosely within the tube in the same 110

manner as the float 25, and the tube 41 is similarly side vented at 42. Two pools of mercury 46 and 46', to which conductors 43 and 44 are respectively connected, are in the bottom, separated by an insulating division wall 41B. Although the level of the pool 46 is above that of the pool 46', the division wall is high enough so that when the float 45 is moved down by the impulse of the entering current of air the mercury does not overflow. The float 45 is transversely grooved at the bottom as shown at 47, to overlie the wall 41B. The bottom of the float carries a conducting element 48 arching over the groove 47 and having projecting points, one of which, 49, is always immersed in the larger pool of mercury 46. The other point, 50, enters the smaller pool when the float 45 is depressed.

It will be seen from the foregoing that the present invention provides a tube construction which maintains all the advantages of a mercury switch operable by differences in air pressure which cause a puff of air or a current of air to strike the upper end of the float but with a simpler tube construction than shown in my co-pending application Serial No. 497,426. Furthermore, the straight tube forms occupy less horizontal space than a J-tube so that they can be put closer together on a board, thus permitting the use of a very compact control board even where the display consists of several hundred or even thousands of individual lamps.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

- 40 1. A switch comprising a tube, a liquid conductor in the bottom thereof, a float on said conductor, means for applying an impulse of air to one end of said float, thereby causing said float to lower in the liquid and so raise the level 45 of said liquid to close a circuit.
- 45 2. A switch comprising a tube, liquid conducting means in the bottom thereof, a float fitting

loosely in said tube and resting on said conductor, means for applying an impulse of air to one end of said float, thereby causing said float to lower in the liquid and so raise the level of said liquid to close a circuit.

3. A switch comprising a tube having a body of mercury in the bottom, an element floating thereon, and pneumatic impulse means for lowering said floating element in the mercury to complete an electric circuit.

4. A switch comprising a tube having a mercury contact in the bottom and an element floating thereon and pneumatic impulse means for lowering said float in the mercury to raise the level of the mercury to complete an electric circuit.

5. A switch comprising a tube, contact points at different levels in the lower part of said tube, conducting liquid in the lower part of the tube below at least one of said contact points, a float resting on said liquid, pneumatic impulse means for increasing the downward pressure on said float to change the level of part of said liquid to make contact between said points.

6. A switch comprising a tube, a liquid conductor in the bottom of said tube adapted to form part of an electrical circuit, a float supported thereby, means for applying an impulse of moving air to said float to lower it and thereby move said liquid conductor mechanically to complete said electrical circuit.

7. A switch comprising a tube, two bodies of liquid conductor in the bottom of said tube, a float supported by one of said bodies, means for applying air movement to said float to lower it and thereby raise the liquid level to bring said bodies into mechanical and electrical contact.

8. A switch comprising a tube, two bodies of liquid conductor in the bottom of said tube, a float supported by one of said bodies, means for applying a current of air to said float to lower it and thereby raise the level of one of said bodies to bring said bodies into mechanical and electrical contact, and means permitting the escape of said air.
